Primary Examiner — Susan Moon Lee*(74) Attorney, Agent, or Firm* — Patent Law Offices of Rick Martin, P.C.**CLAIM**

The ornamental design for a cable dog harness, as shown and described.

DESCRIPTION

FIG. 1 is a top perspective view of my new design for a cable dog harness;

FIG. 2 is a top plan view of my new design for a cable dog harness;

FIG. 3 is a bottom plan view of my new design for a cable dog harness;

FIG. 4 is a rear elevation section view of my new design for a cable dog harness;

FIG. 5 is a rear elevation section view, a continuation from FIG. 4, of my new design for a cable dog harness;

FIG. 6 is a front elevation view of my new design for a cable dog harness;

FIG. 7 is a front elevation section view, a continuation from FIG. 6, of my new design for a cable dog harness; and,

FIG. 8 is a right side elevation view of my new design for a cable dog harness, the left side elevation view being a mirror image thereof.

The broken line elements are not claimed.
